(57) **CLAIM**

The ornamental design for a tray, as shown and described.

DESCRIPTION

FIG. 1 is a perspective view of a tray showing our new design;

FIG. 2 is an alternate perspective view thereof;

FIG. 3 is a bottom plan view thereof;

FIG. 4 is a top plan view thereof;

FIG. 5 is a rear elevation view thereof;

FIG. 6 is a front elevation view thereof;

FIG. 7 is a side elevation view thereof; and,

FIG. 8 is an opposite side view thereof.

The broken lines in the drawings depict portions of the tray that form no part of the claimed design.

1 Claim, 8 Drawing Sheets

Related U.S. Application Data

is a division of application No. 29/811,712, filed on Oct. 15, 2021, now Pat. No. Des. 999,933.
